UNITED STATES PATENT OFFICE.

MAX L. SHIRPSEN, OF SAN FRANCISCO, CALIFORNIA.

MOTOR-METER LOCK.

1,378,288.

Specification of Letters Patent. Patented May 17, 1921.

Application filed March 25, 1920. Serial No. 368,633.

To all whom it may concern:

Be it known that I, MAX L. SHIRPSEN, a citizen of the United States, residing at San Francisco, in the county of San Francisco, State of California, have invented a new and useful Motor-Meter Lock, of which the following is a specification in such full and clear terms as will enable those skilled in the art to construct and use the same.

10 This invention relates to a lock for allowing the removal of a radiator cap carrying a motor-meter which will prevent the removal of the motor-meter from the machine.

It will be understood by those accustomed to automobiles that it is common to provide the radiator cap with a thermometer, but since the radiator cap must be removed from time to time to place water in the machine it is not easy to so lock the cap as to prevent

20 it from being stolen.

The present invention also affords means to support the cap and motor-meter while the radiator is being filled.

Other objects of the invention will appear as the description proceeds.

An embodiment of the invention is shown in the accompanying drawings in which the same reference numeral is applied to the same portion throughout, but I am aware

30 that there may be modifications thereof.

Figure 1 is a side elevation of the front end of a radiator filling neck showing the cap and the application thereto of the securing means.

35 Fig. 2 is a plan view of clamp for embracing the motor-meter.

Fig. 3 is a side view partially in section of the clamp shown in Fig. 2.

40 Fig. 4 is a plan of the ring which is secured to the radiator filling neck and Fig. 5 is a vertical sectional view of the ring shown in Fig. 4.

The numeral 1 indicates the radiator which has the filling neck 2 and cap 3. The

ring 5 which has an upstanding hollow stud 6. The ring 5 is soldered or otherwise permanently secured to the neck embracing the lower portion of the motor-meter. Over the cap is a hinged clamp consisting of the two arms 7 and 8 pivotally connected at 9 and having the overlapping ears 10, 11 and 12 through which a pin 13 passes. The pin 13 passes into the stud 6 and it has a washer 14 permanently secured to its lower end. The washer 14 may be moved vertically in the stud 6 but can not be removed therefrom.

50 The result of the foregoing construction is that the radiator cap can be rotated in the arms 7 and 8 to place it on the neck 2 or to remove it therefrom, but the cap can not be removed from the radiator although it can be turned around out of the way to fill the radiator.

55 What I claim is as follows, but various modifications may be made in the construction shown in the drawings and above particularly described form, within the purview of my invention.

60 1. A securing device for radiator caps comprising a hollow post, a ring connected therewith for permanently securing the post to a radiator outside the filling neck, a pair of arms adapted to be loosely connected with a radiator cap, and a pin for connecting the arms together and to said hollow post, the pin being secured permanently and slideable within said hollow post.

65 2. A securing device for radiator caps comprising a hollow post, a ring connected therewith to be permanently connected to a radiator filling neck outside the same, a pair of pivotally connected arms adapted to be loosely connected with a motor meter on a radiator cap, and a pin for connecting said arms together rigidly, said pin being slideable and revoluble in the hollow post to allow the cap to be moved away from the neck to fill the radiator.

70 In testimony whereof I have hereunto set my hand this 8th day of March, A. D. 1920.

MAX L. SHIRPSEN.
